UNITED STATES PATENT OFFICE.

HENRY LOUIS MARBURGER, OF BALTIMORE, MARYLAND, ASSIGNOR OF ONE-HALF TO
REINLE-SALMON COMPANY, OF BALTIMORE, MARYLAND.

DRUGGIST'S CABINET.

1,219,976.

Specification of Letters Patent. Patented Mar. 20, 1917.

Application filed April 4, 1916. Serial No. 88,873.

To all whom it may concern:

Be it known that I, HENRY L. MARBURGER, a citizen of the United States, and a resident of Baltimore, in the State of Maryland, have made an Improvement in Druggists' Cabinets, of which the following is a specification.

My invention is an improvement in that class of druggists' cabinets containing rows of boxes or drawers arranged contiguously and adapted to be drawn out and turned laterally to expose their open sides and render their contents accessible.

The invention pertains particularly to the improved means for supporting the drawers, while in normal position in the cabinet, also when being pulled out and turned to a lateral position, whereby greater strength, durability, simplicity, and economy of construction are attained.

20 The details of construction, arrangement, and combination of parts are as hereinafter described, and illustrated in the accompanying drawing, in which,

Figure 1 is a perspective view of the cabinet with one drawer pulled part way out and two others pulled completely out and turned to the lateral position, thus exposing their open sides.

Fig. 2 is a vertical section of the cabinet, showing one drawer in section and in normal or closed position, and another pulled out and turned to the lateral position.

Fig. 3 is a section on the line 3—3 of Fig. 2.

35 Fig. 4 is a section on the line 4—4 of Fig. 3.

Fig. 5 is a section on the line 5—5 of Fig. 3.

Fig. 6 is a perspective view showing the 40 bottom portion of a drawer and the slotted metal drawer-guide and support detached.

Fig. 7 is a reduced perspective view showing a drawer pulled out and being turned to lateral position.

45 As shown in Fig. 1, the case or cabinet has horizontal shelves 1, on each of which is a series of contiguous boxes or drawers 2 having one side open and adapted to be pulled out far enough to permit them to

50 be turned laterally so that their contents are accessible and removable. The means of support for each box or drawer 2 and on which they are adapted to slide and turn is a flat, slotted, metal bar, or strip, 3, shown detached in Fig. 6. As may be seen from

Fig. 2, two such supporting guide bars are provided for each drawer, one being secured to the underside of the upper shelf and the other to the upper side of the lower shelf. Thus the two guide bars provided for each 60 drawer are horizontal and parallel and one directly over the other.

The slotted guide bars have an opening at each end to receive screws 4—see Figs. 2 and 5—by which screws they are fastened 65 rigidly to the shelves. A metal washer 5—see Figs. 2 and 5—is applied to each screw 4 between the guide bar and the adjacent shelf to which the said bar is attached, so that the bar is held out of contact with the shelf. 70 The shelves project at the front of the cabinet and the guide bars extend nearly to the outer edge of the shelves, as shown in Fig. 2. Each drawer is slidably or permanently connected at top and bottom to the two over 75 and under guide bars, by means of pivotal screw bolts 6—see especially Figs. 4, 5 and 6.

It will be noted that the washers 5 hold the guide bars 3 spaced from the shelves sufficiently to accommodate the heads of the 80 bolts 6, so that the latter slide easily in the slots of the guide bars.

In Fig. 6 the drawer 2 is shown provided with a groove or rabbet 7 extending along one of its bottom side edges and such groove 85 is enlarged laterally at its inner end, as required to allow the drawer to turn laterally on the outer end of guide bars after it has been drawn out of the cabinet.

It will now be seen that to obtain access 90 to the open side, and thereby to the contents, of the drawer 1, it is pulled forward, by its handle, from its normal closed position into the position indicated in the upper row of drawers in Fig. 1, and in perspective view— 95

Fig. 7—whereupon it is adapted to be swung laterally on its pivots 6, which are then at the outer ends of the slots of the guide bars, and the drawer is thereby turned into position parallel to the face of adjacent 100 drawers, that is to say, parallel to the face of the cabinet, as indicated in the second and third rows of shelves in Fig. 1, and in the sectional views, Figs. 2 and 3. Thus by a direct forward pull and then swinging it 105 laterally, a drawer is placed in position to expose its open side. Thus each drawer in the cabinet is attached to two parallel, fixed, lower and upper, slotted guide bars 3 and is adapted to slide on said bars and to be then 110

turned or swung on the outer ends of the same with minimum friction and wear. Thus a drawer is supported and guided by means of two parallel slotted bars and the 5 same bolts which secure the drawers to the guide bars also constitute the pivots thereof.

I claim:—

10 A druggist's cabinet, comprising a series of horizontal shelves, longitudinally slotted, metal guide-bars secured to, and spaced from, the under and upper sides of adjacent shelves and projecting beyond the front of

the cabinet; slidable drawers having longitudinal grooves at top and bottom for the reception of said guide-bars; and headed 15 bolts which serve as pivots and also as means for securing the drawers to the guide-bars, permitting the drawers to swing laterally in extended position, as described.

HENRY LOUIS MARBURGER.
